G. A. POSS

AUTOMATIC FEED VALVE FOR OIL STOVES

Filed June 4, 1925

Inventor

G.A. Poss

By Watson E. Coleman
Attorney

UNITED STATES PATENT OFFICE.

GRADY A. POSS, OF AUGUSTA, GEORGIA.

AUTOMATIC FEED VALVE FOR OIL STOVES.

Application filed June 4, 1925. Serial No. 34,960.

To all whom it may concern:

Be it known that I, GRADY A. POSS, a citizen of the United States, residing at Augusta, in the county of Richmond and 5 State of Georgia, have invented certain new and useful Improvements in Automatic Feed Valves for Oil Stoves, of which the following is a specification, reference being had to the accompanying drawings.

10 This invention relates to the valves which are used on oil stoves for the purpose of controlling the feed of oil from the main reservoir or tank into the sub-tank, these valves being such that the main reservoir 15 may be taken off for filling and then when the reservoir is inverted the valve strikes the bottom of the sub-tank and is thereby opened and the oil discharged into the sub-tank and to the burners.

20 The general object of the present invention is to provide a feed valve of this character which is so constructed that it will not tend to puncture or wear a hole in the bottom of the sub-tank.

25 A further object is to so construct this valve that it will catch all trash, dirt or other foreign matter which would otherwise pass from the main jar or tank into the sub-tank.

My invention is illustrated in the accompanying drawing, wherein:—

Figure 1 is a perspective view of a portion of an oil stove showing the main tank and sub-tank usually found in these structures;

35 Figure 2 is an elevation of the lower portion of the main tank and the sub-tank, the sub-tank being broken away and the discharge nozzle of the main tank being broken away to show the valve structure 40 therein;

Figure 3 is a vertical sectional view through the valve and allied parts.

Referring to this drawing, it will be seen that I have illustrated one end wall of an 45 oil stove, which is designated 10. This end wall carries the brackets 11 upon which the sub-tank 12 rests and from which a feed pipe 13 extends to the burners (not shown). Adapted to rest upon the sub-tank is the 50 main tank or reservoir 14 which ordinarily is made of glass and is formed with a contracted neck 15 screw-threaded for the reception of a cap, which cap carries the usual valve. This tank 14 is so mounted upon 55 the stove that it may be swung either into an inverted position or swung to a position

with the neck upward, and when in this position the tank 14 may be removed for filling. This construction is commonly found in oil stoves and needs no particular 60 description, as my invention does not relate to any particular means for mounting the tank 14.

The neck 15 is screw-threaded, as before remarked, and engaging the screw-threads 65 of this neck is the cap 16 which is made of thin metal and is provided with a somewhat cylindrical guide 17 having longitudinally extending slots 18. Operating through the central perforation 19 in this cap is the 70 valve rod 20. This valve rod carries the valve 21 and around the valve rod is disposed a coiled compression spring 22, which at its upper end bears against the upper 75 end of the guide 17 and urges downward on the valve 21, thus urging the valve 20 into place on its seat 19. The lower end of the rod 21 carries upon it a cup 23 which, when the tank 14 is inverted upon the sub-tank or bowl 12, bears against the bottom of the 80 sub-tank 12 and causes the valve 20 to open or be lifted against the action of the spring 22, the valve thus remaining open so long as the tank 14 is disposed over the sub-tank 12. Of course, after the usual manner of valves 85 of this character, the valve closes just as soon as the tank 14 is lifted from the sub-tank 12 as, for instance, before filling the tank 14.

It will be seen that the cup 23 rests on the bottom of the sub-tank and the shape 90 of this cup is such as to prevent the valve stem punching a hole in the sub-tank, as it is liable to do where the valve stem is not tilted, as in the present case. By making the shield 23 cup-shaped, any trash or dirt which 95 may pass downward as the oil feeds through the valve opening 19 will be caught in this cup and thus prevents this trash and dirt from stopping up the feed pipe.

While I have illustrated a particular form 100 of valve and a particular form of the shield 23, I do not wish to be limited to this as other forms might be used, but I regard the form of the shield as illustrated as preferable for the reasons stated. While I have 105 designed this valve particularly for use with oil stoves or the like, I do not wish to be limited to this as it may be used in many situations.

I claim:—

1. In an oil burner of the character described, a sub-tank, a main tank invertible

upon the sub-tank and having a neck surrounding an outlet opening, a supporting member mounted in said neck and having an outlet opening, a valve seating within the outlet opening of the supporting member, a spring urging said valve to its seat, the valve having a stem extending beyond the supporting member and adapted to be engaged by the sub-tank when the main tank is inverted therein to thereby open the valve, and a shield carried upon the lower extremity of the valve stem, said shield being in the form of a cup having an area approximately equal to that of the outlet opening of the main tank to thereby receive oil flowing from said outlet opening and detain foreign matter contained within the oil.

2. As an article of manufacture, a valve structure comprising a cap having a screw-threaded flange and a central outlet aperture, a valve stem passing through said aperture and carrying a valve adapted to seat thereagainst, the cap having a guide through which the valve stem passes, a spring surrounding the valve stem bearing against said valve and against said cap to thereby urge the valve to its seat, and a shield carried upon the exterior end of the valve stem, said shield being cup-shaped and having a diameter greater than that of the ordinary outlet opening with which the valve coacts.

In testimony whereof I hereunto affix my signature.

GRADY A. POSS.
